SPARK PLUG CLEANER AND TESTER

Maurice A. Michaels, Montclair, N. J., assignor to
The Oiljak Manufacturing Co., Inc., Montclair,
N. J., a corporation of New Jersey

Application January 14, 1947, Serial No. 721,962

5 Claims. (CL 51-8)

I

The invention disclosed in this patent relates to the cleaning and testing of spark plugs.

Objects of the invention are to provide apparatus for the purpose, in the form of a simple, compact unit which can be quickly and easily set up for use and which will constitute a practical and serviceable unit for efficiently performing all essential spark plug cleaning and testing operations.

In addition to the practical purposes, it is an object of the invention to provide a servicing unit of the type set forth which will be of an attractive design and therefore desirable because of its ornamental appearance and adaptability to display purposes.

Special objects of the invention are to provide a machine in which the cleaning and testing operations can be carried out safely, quickly and conveniently and without requiring special training on the part of the operator.

Other special objects of the invention are to enable quick and easy changeover from the spark plug cleaning to the testing operations and vice versa, to combine with the machine such accessories as may be required for operating on different size plugs and to locate such accessories convenient for immediate use, and generally to provide a machine of simple construction, reasonable cost and otherwise practical and desirable.

Other objects and the novel features through which the purposes of the invention are attained are set forth or will appear in the course of the following specification.

The drawings accompanying and forming part of the specification illustrate one of the present commercial embodiments of the invention. Structure, however, may be modified and changed as regards the immediate disclosure, all within the true intent and broad scope of the invention as hereinafter defined and claimed.

Fig. 1 in the drawing is a plan view of one of the spark plug cleaners and testers, with broken lines indicating how the racks at opposite sides of the machine may be hinged forwardly to expose the adapters or other accessory parts used with the machine;

Fig. 2 is a broken front elevation of the machine;

Fig. 3 is an enlarged side elevation and part broken sectional view of the upper portion of the apparatus;

Fig. 4 is a broken sectional detail showing the hinge mounting for one of the outwardly opening racks or drawers;

Fig. 5 is a further enlarged broken sectional

view on substantially the plane of line 5-5 of Fig. 1;

Fig. 6 is a similar view on substantially the plane of line 6-6 of Fig. 1;

Fig. 7 is a broken cross sectional view on substantially the plane of lines 7-7 of Figs. 3 and 6.

Fig. 8 is a fragmentary plan view showing the air supply passages to the abrasive and cleaning nozzles.

10 In the form of the invention illustrated, the operative parts, in the main, are enclosed within a protective and generally ornamental form of cabinet 10 having a raised central portion 11 carrying the cleaning structure at the back and the testing mechanism at the front and with shoulders at opposite sides of the raised center portion providing shelves or tables 12 and 13 for support of racks or holders for spark plugs, tools or the like.

20 A swinging guard 14 at the back, carried by a pivot stud 15, Fig. 5, urged by a spring 16, covers the spark plug receiving socket and cleaning nozzle when such parts are not in use. This guard, as shown in broken lines in Fig. 1, can be pushed aside against the tension of the spring as a plug is being inserted in the cleaner, and a stop 17 limits the swing in the opposite direction to assure it standing in the protective position at all times when the cleaner is not in actual use.

30 To seal the spark plugs 18 in position in the cleaner, special adapters are employed, constructed as shown in Fig. 5, with a heavy flange or body portion 19, a thin diaphragm wall 20 at the top with a passage 21 to admit the plug and with a thin, flexible, dependent collar portion 22 to enter the annular housing 23 forming a well about the nozzle 24.

40 Holders or adapters 19 for different sizes or constructions of spark plugs preferably are provided and a special feature of the machine is to stack these adapters on a rack or spindle 25, Figs. 3 and 4, on the back of a door 26 set in the front of the cabinet where they will be conveniently at hand for use by the operator.

45 To balance the front of the cabinet and provide accommodation for other accessory parts, a similar door 27 is shown in Fig. 1, pivotally mounted at the right hand side for carrying adapters for use in the testing portion of the equipment.

50 Fig. 4 shows how the doors 26 and 27 may be hingedly mounted at the bottom so as to swing outward like bins, by having projecting pins 28 at the sides which will drop inward and down in bayonet slots 29 in the back of the stationary

flanges 30 at the side edges of the door openings. Projecting stops 31 on the door may engage the edges of stationary flanges 30 to limit the outward swinging movement and stops 32, Fig. 3, at the top may limit the inward closing movement of the doors.

The plug holding adapters 19 may be made of rubber or other resilient material so that the circular thinned lip portion 20, Fig. 5, will yield to and grip the screw threaded base portion of the spark plug and so that the dependent annular flange 22 will closely fit but yieldingly rotate within the housing 23.

To hold the sealing lip 20 in uniformly annular formation when it is stretched by the entered spark plug, there is provided at the under side of the same an annular reenforcing ridge or ring 33, Fig. 5, of larger diameter than the spark plug hole 21 and set far enough back from the spark plug opening to allow the lip to yield downwardly to admit the plug base without becoming distorted or losing its uniformly circular shape. This reenforcing ridge, like the rest of the adapter, may stretch somewhat, if necessary, but it at all times reinforces the thin lip portion, causing it to keep firm sealing engagement with the screw base of the plug.

The nozzle 24 for the cleaning blast is shown in Fig. 5 as a flanged bushing of rubber or like material thrust upwardly through an opening in the top of the nozzle housing 34, directly above the air jet nozzle 35 at the end of the upwardly directed air duct 36.

A tube 37 extending downwardly from within the nozzle housing into the abrasive holder 38, supplies the abrasive for the cutting and cleaning blast and an upwardly directed nozzle passage 39 from a second air duct 40 provides the blast for cleaning purposes.

A nipple 41, Figs. 1 and 2, on the side of the head provides means for connecting the unit with a compressed air supply source. At the inside this supply nipple is connected with a water trap 42, from which branch supply piping 43, 44, extends forwardly to the cleaning and testing elements, respectively.

Fig. 5 shows the air tubing 43 connected with a manifold 45 having one branch 46 with a valve 47 controlling admission to the duct 36 supplying induction air for the abrasive. In similar manner, another branch 50 controlled by a valve 51, supplies air to the duct 40 for the air blast cleaning nozzle 39.

Both air valves are alike, consisting, as shown in Fig. 5, of a downwardly opening valve, 47 in this particular case, on the lower end of a vertically sliding stem 52, said valve being seated upwardly by a light spring 53 and adapted to be opened downwardly by a heavier spring 54 bearing on the head 55 at the upper end of the valve stem and adapted to be pressed downwardly by a button 56 engaged by a finger lever, 57 in the case of the abrasive jet and 58 in the case of the air cleaner jet, Fig. 1.

Fig. 5 shows how the finger levers are pressed upwardly by the spring supported valve operating buttons against an overstanding cover or housing 59, and also how the inner ends of such levers are rounded at 60 to operate as pivot fulcrums in the correspondingly rounded seats 61 at the under side of the cover housing. In this view, also, there is shown one of the screws 62, of which there may be two or more, for securing the cover housing 59 down over the top of the cabinet. This screw or screws may pass

down through the flange 63 of the adapter sleeve 23 seated on the cover member 59, to enable one set of screws to secure both parts in position and in so doing to secure and pivotally mount the finger levers 57, 58, in operating position over the valve stems.

The hinged guard 14 is shown in Fig. 5 as mounted on the hollow cover member 59, so that the removal of one set of screws 62 enables an entire group of parts to be taken off. At the same time these holding screws are normally cut of sight, beneath the flange of the spark plug adapter 19.

The air line 44 is shown in Figs. 3, 6 and 7, as connected at the front with a manifold 64 branched at 65, 66, to the test heads 67, 68.

The latter are shown in Figs. 6 and 7 as socketed to receive screw adapters 69 for different kinds of spark plugs.

The inner ends of the test chambers 67, 68, are closed by transparent covers 70 and these ends of the chambers are opposite an inclined reflector 71 on the front wall of the cabinet top, Figs. 1 and 2, so that the action of a cleaned plug or plug under test can be compared with a new or standard plug.

To enable quick change-over in making the comparative tests, a sliding and swinging connector is provided, in the illustration, in the form of a rod or post 72 slidingly and rotatably guided in a sleeve 73, Fig. 6, in the front of the cabinet head, said post carrying a low tension cable 74 and push-button switch 75 and a high tension cable 76 continuing through a laterally extended arm 77 to a terminal 78 engageable with the end of a spark plug seated in either of the testing sockets.

As shown in Fig. 6, the control switch 75 is located in a central knob extension 79 of the insulating support, providing a convenient grip for sliding and turning the support to bring the end contact 78 into and out of engagement with spark plugs seated in the test chambers. This switch serves to connect the wires 80 of the primary low tension circuit and, located as shown, is in convenient position for the button of the same to be actuated by a finger of the hand grasping the knob 79.

The necessary electrical connections are indicated in a general way in Fig. 3, where an extension cord is shown at 81, provided with a terminal plug 82 for engagement in an outlet receptacle, said cord being connected at one side at 83 with the primary winding of a spark plug transformer 84, the other side, 85, of such primary winding and the other side, 86, of the cord circuit being connected with the two wires 80 of the low tension cable 74 running through the insulator 72 to the push-button switch 75.

The high tension lead 76, carried by the insulating support 72, is indicated as extended at the back direct to the high tension terminal of the transformer 84, enough slack being left in the free portions of both the low and the high tension cables 74 and 76 to allow for the in-and-out sliding and the rotary movements of the insulating support or carrier 72.

A spring 87, Fig. 6, surrounding the inner end of member 72 and interposed between the inner wall of the casing and an abutment washer 88 on the member 72, serves to yieldingly retract the latter and temporarily retain it in positions in which it may be set.

The member 72 thus serves, in effect, as an insulating handle normally retracted in the hous-

ing, which can be drawn out, partly rotated to line up the arm 77 with a spark plug in one of the pressure chambers 67, 68, and released to enable the spring 87 to hold the high tension terminal 78 in engagement with the terminal of the spark plug. Then, or as a part of the same act of establishing connection with the spark plug, the switch button 15 on the knob-like end of the carrier handle can be pressed to close the primary circuit and hence induce a discharge through the high tension lead to the selected spark plug.

By carrying both primary and secondary circuits through the insulating selector handle, with the means, switch 15, for closing the primary circuit and the means, contact 18, for closing the secondary circuit, all controls and connections can be effected from this single handle. Both circuits are normally open and the only switch is in the low tension primary side of the spark supply connections. This keeps the operator safe against shock. Inward pressure on the switch to close the primary circuit serves to press the high tension contact all the more firmly against the end of the spark plug, assuring good connection for the testing operations.

The holder for the abrasive, generally designated 38, has a wall of filter cloth. This wall, designated 89 in Fig. 5, may be fibreglass supported by nylon.

The invention provides, in attractive cabinet form, a completely self-contained unit for either or both cleaning and testing spark plugs and which can be made immediately available by simply plugging it into an electric outlet, at 82, and connecting on an air hose, at 41.

The cleaning and testing operations can be quickly effected by changing the plugs from one to a closely adjoining station. The plugs are completely sealed in at the cleaning station so that the operations there of scouring with abrasive and then cleaning with the air blast, are quick, clean and safe. In the scouring operation, the holder or adapter 19 in which the plug is sealed may be rotated with the fingers one or more turns in the holding socket 23, to assure presentation of all parts of the plug to the blast jet.

The operations are completely and conveniently under control of the operator through selective use of the finger keys 51, 58. The automatically closing guard 14 avoids possibility of discharge of the blast through accidental operation of the control keys.

All parts are of simple, rugged design, easily assembled and, if necessary, disassembled. Furthermore, all operating parts are contained within the cabinet structure, protected and out of the way, leaving the cabinet exteriorly unimpeded, smooth and generally attractive in appearance.

Necessary accessory parts such as adapters for the plugs at the cleaning and testing stations, while normally housed and out of the way, are conveniently available on the backs of the outwardly swinging doors 26 and 27.

The adapters 19, as shown in Fig. 5, bear directly on the supporting flange 63 of the cleaner housing 23, assisting the dependent annular wall 22 in providing a proper rotary seal, and the laterally extended flange portions of the adapters in this relation provide convenient finger grip portions for turning the adapters and thus exposing all portions of the supported spark plugs to the abrasive and cleaning blasts.

What is claimed is:

1. A spark plug cleaner comprising an upwardly directed cleaning nozzle, a casing form-

ing a socket about the same and a spark plug holder having a thin yielding top diaphragm wall with a spark plug receiving opening therein to form a lip for sealing engagement with the base portion of a spark plug and a dependent annular wall rotatably seated in sealing engagement in said socket and said holder having a laterally projecting thick flange portion bearing on top of said casing and providing a finger hold by which said holder may be rotated to turn the plug over the nozzle and said holder having a yielding top wall of the holder having a reinforcing rim about and spaced radially outwardly of the spark plug receiving opening in said flexible sealing lip to prevent deformation of the latter.

2. A spark plug cleaner comprising a casing having a well in the top of the same, a spark plug holder rotatably seated over said well, abrasive and air jet nozzles directed upwardly into said well, valves controlling said nozzles and finger levers fulcrumed at one side of said well and arranged to selectively actuate the valves controlling said nozzles, a casing about said well and extending over said finger levers, said levers having rounded inner end portions

25 to form the fulcrums for said levers and the overstanding portion of said casing having seats for said rounded fulcrum portions and said valves having springs thrusting against the levers to hold said fulcrum portions seated and whereby said levers may be mounted and properly positioned by simply engaging them with the spring pressed valve stems and securing the confining casing over the same.

3. A spark plug tester comprising a pair of spaced spark plug testing sockets, a quick change-over connector comprising an insulating support carrying a high tension terminal for engagement with the end of a spark plug seated in either of said testing sockets and mounted for quick shifting movement to engage said terminal with the end of a spark plug in either of said sockets, high and low tension electric connections carried by said insulating support including a high tension connection extending to said terminal and a manually operable switch controlling said low tension connections and mounted on said support in position for convenient manual operation.

4. A spark plug tester comprising a pair of spaced spark plug testing sockets, a quick change-over connector comprising an insulating support carrying a high tension terminal for engagement with the end of a spark plug seated in either of said testing sockets and mounted for quick shifting movement to engage said terminal with the end of a spark plug in either of said sockets, high and low tension electric connections carried by said insulating support including a high tension connection extending to said terminal and a manually operable switch controlling said low tension connections and mounted on said support in position for convenient manual operation, said insulating support having a rotatably and slidably mounted post portion and an arm projecting laterally therefrom and carrying said high tension terminal and said switch being mounted at the end of said post portion in position for actuation by a hand rotating and sliding the support in shifting the high tension terminal from one spark plug to the other.

5. A spark plug tester comprising a pair of spaced spark plug testing sockets, a quick change-over connector comprising an insulating support carrying a high tension terminal for

engagement with the end of a spark plug seated in either of said testing sockets and mounted for quick shifting movement to engage said terminal with the end of a spark plug in either of said sockets, high and low tension electric connections carried by said insulating support including a high tension connection extending to said terminal and a manually operable switch controlling said low tension connections and mounted on said support in position for convenient manual operation, said insulating support having a post portion and a laterally projecting arm carrying said high tension terminal and said post portion being rotatably supported to swing said laterally projecting arm over from a spark plug seated in one socket to a spark plug seated in the other socket, said post being further mounted to slide to carry said laterally projecting arm longitudinally toward and away from spark plugs seated in said sockets and spring means acting

on said support to slide the same toward the testing sockets.

MAURICE A. MICHAELS.
